PORTABLE ELECTRIC LIGHTING OUTFIT

Abraham Abramson, New York, N. Y., assignor to
 Raylite Trading Company, Inc., a corporation
 of New York

Application June 18, 1934, Serial No. 731,020

3 Claims. (Cl. 248—42)

This invention relates to electric lighting sets and more particularly is directed to an improved construction of portable lighting outfits for display and ornamental illumination such as used for Christmas tree decorations and other purposes.

Among the objects of the invention is to generally improve sets of the character described including an improved device comprising few and simple parts which are readily assembled to permit easy mounting and securing the light sockets and wiring of such sets to the branches of the trees or other supports, which devices shall serve as ornamental trimmings, and which shall be efficient and practical to a high degree in use.

Other objects of this invention will in part be obvious and in part hereinafter pointed out.

The invention accordingly consists in the features of construction, combinations of elements and arrangements of parts which will be exemplified in the constructions hereinafter described and of which the scope of application will be indicated in the following claims.

In the accompanying drawing, in which is shown various possible illustrative embodiments of this invention,

Fig. 1 is a perspective view of a branch of a Christmas tree on which is shown a portion of a portable electric lighting outfit constructed and mounted to embody the invention.

Fig. 2 is an enlarged front elevational view of one of the light sockets and portion of the wiring of the lighting outfit shown in Fig. 1.

Fig. 3 is a cross sectional view taken on lines 3—3 in Fig. 2.

Fig. 4 is a sectional view of the bead of the improved mounting device shown in Fig. 2.

Fig. 5 is a perspective view of the ring clip of said improved device.

Fig. 6 is a top plane view of a modified form of improved ornamental mounting device having a split bead.

Fig. 7 is a top plane view of the split bead shown separated.

Fig. 8 is a fragmentary view showing another modification of the invention.

Fig. 9 is a top plane view of the bead of the improved device shown in Fig. 8.

Fig. 10 is a top plane view of the improved ornamental mounting device like that shown in Fig. 8, except that the clip is located at right angles to the through passage, and

Figs. 11 and 12 are front elevational and top plane views, respectively, of still another modified

form of improved ornamental mounting device using a larger and more conspicuous bead.

Referring in detail to the drawing, 20 denotes electric lamp sockets forming portions of a circuit of a portable electric lighting set such as a Christmas tree lighting outfit, the latter being provided with ornamental mounting devices for securing flexible conductor wires 21 thereof to a support, such as the branches B, as shown in Figs. 1 to 3, inclusive, and in the manner to embody the invention.

As shown such ornamental mounting device comprises a bead 22 preferably formed of an insulated decoratively colored material such as wood, fibre, glass, porcelain, phenol-condensate products, rubber and the like. Said bead has an axial passage 23 wherethrough one of the flexible conductor wires 21 passes and has a circumferentially formed groove 24. Seated in said groove 24 is an open-ended metallic wire ring member 25 formed at one end with a spring clip 26. The latter is hook shaped and is adapted to clampingly engage the branch B of the tree T as shown in Figs. 1, 2 and 3.

The practical application of the invention will now be apparent. Mounting devices having beads 22 of a color or colors desired to contrast or harmonize with the surrounding decorations are threaded on either or both conductor wires 21. With said devices located on the wires 21 adjacent the sockets 20, the latter are secured in position on the branches B by means of the clips 26. With said devices located at spaced distances from such sockets, loose conductor wires 21 are neatly retained in place by said clips 26.

Said devices are particularly desirable and convenient to use since they permit ready means for mounting the light sockets and conductor wires of the outfit to conform with various decorative schemes, the beads 22 thereof being adaptable to provide artistic ornamental trimmings.

In Figs. 6 and 7, a modified construction of the mounting device is shown having split or mated half beads 32. Here an open-ended ring member 35 formed with a spring clip 36 which lies in the plane of said member 35 is used. This location of the clip, instead of having the same extending at right angles to the ring member as shown in Fig. 2, is sometimes found more convenient for mounting the light sockets 20 to extend in particular directions. The split bead construction is preferable for outfits already assembled since the device can be easily applied without disconnecting the wiring. With the split

beads, the axial passages 33 may be made non-circular in cross sections and of such proportions as to provide frictional engagement on the conductor wires 21, the ring member 35 being constructed to compress the bead halves and retain the devices in any set position along the conductor wires 21.

Another form of the invention is shown in Figs. 8, 9 and 10. Here the bead 42 besides having a passage 43 for receiving the conductor wires 21 has another through opening 44 wherein one end 45a of a U-shaped wire member 45 is anchored, the other end 45b of said member serving to clampingly retain the support B in the bend on loop 45c as is clear from Fig. 8. The end 45a may be swivelly retained in the opening 44 to permit angular adjustments of the mounting device with respect to the support B.

Where it is desired to use a larger and more conspicuous ornamental trimming, the modified form of the mounting device shown in Figs. 11 and 12 is used. Here there is provided a large oval shaped bead 52. A passage 53 extends through the long axis and a groove 54 is formed about the short diameter. The ring member 55 is seated in the groove 54 and has a spring clip 56 located to lie in the plane of said member 55 like in the form of invention shown in Fig. 6 and described above.

Each of the mounting devices shown in Figs. 4 to 12, inclusive, are used in the same manner described above for and shown in Figs. 1 to 3, inclusive.

It will thus be seen that there is provided a device in which the several objects of this invention are achieved and which is well adapted to meet the conditions of practical use.

As various possible embodiments might be made of the above invention and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. A mounting device for a portable electric lighting outfit comprising a bead having a passage therin adapted to receive a conductor wire of said outfit and having an opening spaced from said passage, and a clip anchored in said opening to extend from said bead for securing the portions of the wire passing through the passage to the support. 80

2. The device defined in claim 1 in which the clip is swivelly secured in its anchorage. 85

3. In a Christmas tree lighting outfit comprising a plurality of light sockets in series and flexible conductor wires connecting the same, a plurality of mounting devices carried by said wires for attaching said wires to said tree and for suitably mounting said sockets, each of said devices comprising a bead and a clip, said bead having a passage receiving the conductor wire and a recess receiving the clip, the clip consisting of a length of wirelike material having an annular portion engaging said bead in said recess and having an immediately adjacent hook-like part to resiliently engage a part of the tree, whereby the sockets and the conductors may be firmly mounted on said tree in any manner desired. 90
